Des. 204,290
Patented Apr. 5, 1966

204,290

WIRE CARRIER

Robert Kohn and Mortimer C. Winski, Michigan City,
Ind., assignors to Northern Indiana Steel Supply Co.,
Inc., Michigan City, Ind., a corporation of Indiana

Filed Jan. 25, 1963, Ser. No. 73,316

Term of patent 3½ years

(Cl. D41—1)

FIG. 1

FIG. 2

FIG. 3

FIGURE 1 is a perspective view of a wire carrier embodying the present novel design;

FIGURE 2 is a side elevational view of the wire carrier shown in FIGURE 1;

FIGURE 3 is a top plan view of the wire carrier shown in FIGURES 1 and 2.

We claim:

The ornamental design for a wire carrier, substantially as shown.
